CLAIM

The ornamental design for a refrigerator as shown and
described.

DESCRIPTION

FIG. 1 is a perspective view of a refrigerator according to the
claimed design;

FIG. 2 is a perspective detail view thereof within area 2, as
indicated in FIG. 1;

FIG. 3 is a front elevation view thereof;

FIG. 4 is a front elevation detail view thereof within area 4,
as indicated in FIG. 3; and,

FIG. 5 is a further front elevation detail view thereof within
area 5, as indicated in FIG. 4.

The portions of the article shown in broken line form no part
of the claimed design.

Dash-dot lines adjacent un-shaded areas represent bounds of
the claimed design and form no part of the claimed design
themselves.

The dash-dot-dot type broken lines represent bounds of the
isolated views only and form no part of the claimed design.
